UNITED STATES PATENT OFFICE

THEODORE J. GRYPMA AND MARTIN MEULENBERG, OF GRAND RAPIDS, MICHIGAN

SANITARY TOILET SEAT DISPENSER

Application filed April 7, 1931. Serial No. 528,374.

This invention relates to certain novel improvements in sanitary toilet seat dispensers, and has for its principal object the provision of an improved construction of this character which will be highly efficient in use and economical in manufacture.

Among the several objects of this invention is the provision of improved means for supporting, adjacent a toilet seat, a roll of paper having previously formed openings at intervals therein, and to provide means by which a section of said paper having one of said openings therein may be conveniently withdrawn and severed from the roll so that said severed section may be disposed on the toilet seat.

Another object of the invention is to arrange the invention in such a manner that the end of the roll may be conveniently grasped after a section thereof has been severed so that other and additional sections may be withdrawn from and severed from the roll.

A further object of the invention is to provide means by which a drag will be exerted on the paper roll as the same is withdrawn from its housing so that an undesirably long section of paper will not be withdrawn from the roll in the use of the same.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a perspective view of a preferred form of construction of our improved dispensing device showing a section of the paper roll in association with a toilet seat of convenient design;

Fig. 2 is a sectional detail view of the dispensing device and paper roll, taken substantially on the line 2-2 in Fig. 1;

Fig. 3 is a top plan view, partly in section, of the dispensing device, taken substantially on the line 3-3 in Fig. 2;

Fig. 4 is a longitudinal sectional view of the dispensing device; and

Fig. 5 is a sectional view of one end of the dispensing device, taken substantially on the line 5-5 in Fig. 4.

Referring to the drawing, wherein a preferred form of construction of the invention is depicted, generically indicated at 10 is a toilet bowl of conventional design which includes the hinged seat 11 and cover 12. Usually disposed adjacent the bowl 10 is the flushing tank 13. The present invention provides a roll of paper 14 at intervals in which are provided previously stamped or cut openings 15 that are adapted to be disposed over the seat 11, and the means provided by the invention for supporting the roll and severing a section therefrom will now be described.

The dispenser provided by the present invention is generically indicated at 16 and is intended to be fastened to the floor adjacent, and preferably at the right side of the bowl 10, though the dispenser 16 may be arranged at either side of the bowl 10, or at the rear thereof, as the design of the bowl and appurtenances therefor warrant.

The dispensing device 16 includes a supporting base 17 which may be secured to a supporting floor or surface in any suitable manner, as by bolts 18. Integral with, and extending upwardly from the base 17, is a supporting leg 19, on the upper end of which is mounted, in any suitable manner, an arcuate support 20 which is secured to the roll housing 21 by suitable bolt and nut structures 22.

The roll housing 21 is in the form of a cylindrical drum and includes the lower semi-circular half 21a and the upper half 21b which provides a cover that is hingedly connected to the lower section 21a by any suitable type of hinge construction such as pintle 23 and buckles 24.

The drum 21 includes end walls 25 and 26 which include flanges 25' and 26' that are secured to the section 21a of the drum in any suitable manner, as by soldering. Disposed inwardly of the end walls 25 and 26, and each having a flange 27 that is secured to the section 21a of housing 21 in any suitable manner, as by soldering, are roll guiding plates 28, in each of which is provided a slot 29 and

aligned with each of the slots 29 are slots 30 formed in the end walls 25 and 26, for a purpose to be made apparent presently. A roll of paper 14 is intended to be disposed 5 in the housing 21 between plates 28 and to be withdrawn therefrom through means to be described hereafter, and it will be seen that by looking through either pair of slots 30 and 29 the amount of paper left in the 10 roll at any particular time, and the need for replacing the same, may be determined without the necessity of opening the housing, the advantage of which will be made apparent hereinafter.

15 A guiding flange 31 includes a portion 44 that is secured to the free end and the inner side of the cover 21b by means of suitable bolt and nut structures 32 or the like. At the outer end of the flange 31 a serrated 20 cutting blade 33 is secured by means of screws 34 or the like. Formed in the end portions of the flange 31 are recesses or notches 35. The lower and stationary section 21a of the drum 21 has integral therewith an outstanding flange 36 which extends parallel to but spaced from the flange 31 to provide a guideway and outlet 37 through which the paper 14 may be withdrawn from the drum 21. The notches 35 provide similar pairs of ears 40 in 25 the ends of the flanges 31 and 36 and suitable aligned openings are provided in these ear portions 40, and the bolts 41 extend through these openings and have wing nuts 42 thereon. Spring leaves 43 are secured to the portion 30 44 of the flange 31, and to the cover 21b of the drum, by means of suitable bolt and nut structures 45, or the like, and by reference to Figs. 2 and 3, it will be seen that these spring leaves 43 include portions 46 that 35 extend into the guideway 37 so as to bear upon the paper 14 as the paper is withdrawn through the guideway 37. In this manner a drag is exerted upon the paper 14 by the spring leaf portions 46 so that by grasping 40 with the thumb and index finger the portions of the paper 14 that are accessible through the recesses 35 a suitable length or section of the paper may be withdrawn, and when a suitable section of the paper 14 has been 45 withdrawn, such section may be severed by lifting upwardly on the outer end of the withdrawn section so as to sever the section by means of the serrated edge 47 of blade 33. After such section has been severed from 50 the roll, the paper 14 will again be accessible 55 through the recesses 35 (Fig. 3).

It is apparent that by removing the wing nuts 42 the upper section 21b of the drum may be lifted, with flange 31, so as to replace the roll 14 when desired.

The hereinbefore described invention provides a simple and efficient device for dispensing sanitary toilet seat paper and provides means whereby such paper may be manufactured in rolls having openings therein

at regular intervals so that by the use of the device a section of said paper having one of said openings therein may be conveniently withdrawn and severed from the roll when desired. The device may, as is apparent from 70 the drawings and the above description, be used with any style or design of bowl.

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claim.

Having thus described our invention what we claim as new and desire to protect by Letters Patent is:

A dispensing device for sanitary toilet seat covers arranged in rolls comprising a drum including a stationary section and having an open upper side, and including a closure member hingedly connected to said section to close said open side, a flange member carried by the free end of said closure member and projecting radially from said drum, a flange member on said stationary section arranged in parallelism with said first-named flange member and cooperating with said first named flange member to provide a guideway through which the free end of said roll may be withdrawn from said housing, said flange members having finger notches in the ends thereof so that the paper may be grasped by the fingers, and resilient members carried by the closure member and having portions disposed in the guideway to exert a drag upon the paper therein.

In testimony whereof we affix our signatures.

THEODORE J. GRYPMA.
MARTIN MEULENBERG.
